INVENTOR

Patented Nov. 29, 1927.

1,650,908

UNITED STATES PATENT OFFICE.

GEORGE RAMSEY, OF BROOKLYN, NEW YORK.

METHOD AND APPARATUS FOR IDENTIFYING AMMUNITION.

Application filed September 3, 1924. Serial No. 735,553.

The present invention relates broadly to ammunition and more specifically to the method and means for identifying parts of the same after it has been fired.

- 5   Ammunition for small arms is frequently used by unauthorized persons or irresponsible persons or others for criminal purposes, and criminologists then attempt to identify the projectile or the shell from which the
10   projectile has been fired by trying to find impressed upon either the projectile or the shell some accidental individual characteristic of the gun or pistol from which the ammunition was fired.
15   The present invention facilitates the identification of the particular projectile or shell by providing specified identification marks by which the ammunition may be registered, and which is so constructed that identifying
20   marks may either be impressed by the firing of the ammunition or be an assembled part of the ammunition, so that identity of the person firing the ammunition may be easily ascertained, by tracing the identified ammunition.
25

- The present invention may be embodied in forms other than those herein specifically disclosed, which are merely illustrative, but in a broad sense, it comprises assembling the
30   ammunition with marked parts, for example, suitable identifying numbers on the bullet or suitable identifying numbers on small thin discs of material which will be scattered to the four winds when the ammunition
35   is fired, then imposing the same marking upon the box in which the ammunition is packed. The box may be registered as to the buyer by the manufacturer of the ammunition, and then by the retailer to the re-
40   tail buyer who purchases the individual box, and thus the ammunition may be traced when used.

In one form of the present invention, all of the ammunition in one box, for example, 45 fifty shells, shall be marked with the same identifying number so that any one of these fifty shells, when fired will project either a marked bullet of a designated number or a marked wad of a large quantity of numbered sheets of material, all of which bear the same designating number, which sheets will scatter when the ammunition is fired. This designating number is the same for all the fifty cartridges in the box.

55   Another feature of the present invention is the impression upon the shell of the num-

ber of the pistol or gun from which the shell is fired. This may be accomplished by providing suitable marking means carried by the gun or pistol and so positioned that the 60 gas pressure produced by firing the ammunition causes the shell to be forcibly brought into contact with the designating numbers which are impressed on some portion of the shell.

65   Referring now to the drawings which disclose preferred embodiments of the invention;

70   Fig. 1 illustrates a bullet with the designating number impressed on the base thereof;

75   Fig. 2 is a compact wad of sheets of material, each sheet of which bears a common designating number;

80   Fig. 3 illustrates the wad shown in Fig. 2 broken into its separate sheets as it will be when the ammunition is fired;

85   Fig. 4 illustrates a jacketed bullet with the designating number on the rim of the jacket at the base of the bullet;

90   Fig. 5 is a partial cross-section through a cartridge loaded with a designating wad, shown in Fig. 2;

95   Fig. 6 illustrates a bullet with a depressed groove or band in which the designating members are impressed sufficiently deep to prevent the numbers being cut away by the rifling when the ammunition is fired;

100   Fig. 7 illustrates a cartridge box filled with designated cartridges;

105   Fig. 8 is a section through a portion of the frame of a pistol or revolver showing matrix numbers so arranged that these numbers will be impressed on the base of a shell fired in this pistol;

110   Fig. 9 is a detailed sectional view illustrating the construction in Fig. 8;

115   Fig. 10 is an enlarged view of a designating number disc or ring adapted to be set in the frame of a gun or pistol;

120   Fig. 11 illustrates a shell of a cartridge which has been fired in a gun equipped with the designating matrix numbers arranged as shown in Figs. 8 to 10;

125   Fig. 12 illustrates a revolver being fired, and showing the scattering of the sheets forming the wad shown in Fig. 2;

130   Fig. 13 illustrates a section of the firing chamber of a gun with the designating matrix numbers arranged in such manner as to be impressed upon the side of a shell of a cartridge fired in the chamber;

Fig. 14 illustrates a shell of a cartridge fired in a chamber such as shown in Fig. 13.

The present invention comprising the individual marking of the elements of a cartridge, and includes a method which may be carried out during the loading of the ammunition so that as the bullets are to be fed to the shells by a loading machine suitable markings are impressed on the bullets and 10 a similar mark may be impressed on the box in which a predetermined number of such marked bullet cartridges are to be packed.

In Fig. 1, the bullet 1 is marked by impressing the numerals 2 on the base of the 15 bullet and a filler line 4 fills the remaining space to indicate the absence of higher numbers. In Fig. 4, the jacketed bullet 5 is shown with designating numerals 2 and the 20 filler line 4 as being on the edge of the jacket for the bullet. This jacket is usually made of harder material than the lead in the bullet and the numbers stamped in this edge are not likely to be destroyed during firing.

Referring to Figs. 2, 3 and 5, a wad 6 is 25 composed of a plurality of thin sheets of material, each sheet of which bears the designating numerals 2 and filler line 4, and these sheets are loosely assembled and preferably set in the loaded cartridge 7 between 30 the powder 8 and the bullet 1 so that when the shell is fired, as in a revolver 9, Fig. 12, the individual sheets will be so scattered about that it would be difficult for one firing 35 the ammunition to find and pick up all of the sheets, thereby leaving evidence of the fact that a particular designated cartridge was fired at that spot, and if the number of the cartridge was registered by the dealers, the person who bought the cartridge may be 40 easily ascertained.

Fig. 7 illustrates a filled cartridge box 10 which bears a number 11 indicating the number of loaded cartridges in the box and also 45 the designating numeral 2 which designates the characteristic marking of every shell in the box, so that when each cartridge in the box is fired, the bullet may bear the same designating number and also where desired, 50 designating wads of sheets will also carry the same designating number as that on the parts.

Fig. 6 illustrates a bullet 1 provided with 55 a groove 12 with the designating number 2 impressed on the base of the groove. This groove is of sufficient depth so that the designating number will not be destroyed by the rifling in the barrel of the pistol or gun.

Figs. 8 to 14 illustrate constructions whereby the shell of a cartridge fired in a pistol 60 or gun is automatically marked during the firing operation to indicate the particular pistol from which the cartridge was fired, and preferably, the designation comprises the serial number of the pistol or gun. This 65 designation may be obtained in various

ways, but preferably comprises mounting designating numbers in the pistol or gun in such manner that the pressure produced during firing of the cartridge will impress on the empty cartridge the serial number of 70 the gun or pistol. This may be accomplished in one form by providing a disc or ring 14 on which matrix numbers 15 stand in relief, and this disc 14 may be provided with an opening 16 for the firing pin 17 of the 75 weapon. This disc 14 is adapted to be set into the frame 18 directly back of the head of the cartridge so that the cartridge is supported by the disc and the matrix numbers thereon when gas pressures develop during 80 the firing of the cartridge. When the cartridge is fired, the force of the explosion impresses the matrix numbers on the head 19 of the shell thereby impressing the serial number 20 of the gun or pistol on the head 85 of the shell.

In Figs. 13 and 14 are illustrated an arrangement whereby the marking of the shell occurs on the side thereof and in this form, the firing chamber of the barrel 21 of the 90 gun is provided with a sleeve 22 on which are arranged matrix numbers 15 preferably comprising the serial number of the pistol or gun and when the cartridge is fired, this number is impressed as at 24 on the side of 95 the shell, so that any shell fired in this particular weapon will bear that designating numeral. This form may be especially useful in connection with automatic pistols or guns which may use ammunition which bears 100 the maker's name on the head of the cartridge. By this form of the invention where the number or designating character is impressed on the side of the shell, it leaves a mark which is not interfered with by ammunition makers' designations such as are 105 usually provided on the heads of central fire cartridges.

Furthermore, this invention may have a further utility by being used to impress the 110 name of the gun maker upon each shell fired. This has the advertising value of scattering parts of used ammunition, each of which is marked with the name of the maker of the gun used.

Having thus described my invention, what 115 I claim is:—

1. The method of rendering parts of ammunition easy of identification after use, which comprises impressing an identifying 120 mark upon such parts when the ammunition is fired.

2. The method of rendering parts of ammunition easy of identification after use, which comprises impressing a serial number 125 upon such parts during the firing of the ammunition.

3. The method of rendering parts of ammunition easy of identification after use, which comprises rendering identifying fig- 130

- ures on such parts effective for identification by the firing of the ammunition.
4. The method of rendering parts of ammunition easy of identification after use, which comprises automatically impressing upon such parts, at the time of firing of the ammunition, identifying figures characteristic of the firearm in which the ammunition is fired.
5. The method of rendering parts of ammunition easy of identification after use, which comprises utilizing the explosive pressure of the ammunition to effect the impression of an identifying mark upon a part of said ammunition.
6. The method of rendering easy the identification of the firearm from which ammunition was discharged, which comprises utilizing the explosive pressure of the ammunition to effect the impression of a serial number of the firearm employed upon an element of the ammunition discharged.
7. In a cartridge for firearms, an element for identifying the cartridge after firing, said element carrying a series of identifying figures and a filler line at each end of the series to indicate the absence of additional figures in the series.
8. In a cartridge for firearms, an element for identifying the cartridge after firing, said element carrying a series of identifying figures and means at each end of the series to indicate the absence of additional figures in the series.
9. In a cartridge for firearms, a laminated wad for identifying the cartridge after firing, the various laminæ of the wad carrying common identification numerals and a filler line to indicate the absence of additional numerals in each series.
10. A firearm comprising means to impress an identifying mark upon ammunition fired therein.
11. A firearm comprising means to impress serial number upon ammunition fired therein.
12. A firearm comprising an explosion chamber having a marking portion on the wall thereof, said marking portion being adapted to impress an identifying mark 50 upon a shell exploded in said chamber.
13. A firearm comprising an explosion chamber having raised numerals on the wall thereof, whereby when a shell is exploded it is pressed against the raised numerals and 55 receives an identifying mark.
14. The method of identifying discharged small arm ammunition which comprises providing identifying means, and utilizing the explosion of the ammunition to render the 60 identifying means effective.
15. The method of identifying discharged small arm ammunition which comprises, providing identifying means, and utilizing the gas pressure of the explosion of the ammunition to render the identification visible. 65
16. The method of identifying discharged ammunition with the gun firing the same, which method comprises providing identifying means on the gun so located as to cause 70 a permanent identification mark to be imposed on a part of the ammunition when the same is fired in such gun.
17. The method of identifying cartridge ammunition comprising marking a portion 75 of the projected charge with visible serial markings, packing the marked portion within the shell of the cartridge to render the same inaccessible without disassembly of the cartridge, and keeping a record of the disposition of the serially marked ammunition.
18. In an ammunition cartridge, the combination of a shell, an explosive charge, a charge adapted to be projected from the shell and comprising numerous small light 85 weight members placed within the shell, each member bearing the same visible serial designating mark, said mark being one of a series of recorded marks so that any one of said members so identifies said cartridge as 90 to enable the history of the same to be traced.

GEORGE RAMSEY.
